UNITED STATES PATENT OFFICE

CARL D. BROWN, OF HOPEDALE, MASSACHUSETTS, ASSIGNOR TO DRAPER CORPORATION, OF HOPEDALE, MASSACHUSETTS, A CORPORATION OF MAINE

AUTOMATICALLY-THREADING LOOM SHUTTLE

Application filed February 24, 1930. Serial No. 430,502.

This invention relates to automatically threading shuttles and is more particularly directed to means for exerting uniform tension on the thread during weaving.

In order that perfect cloth may be woven, the tension exerted on the thread following replenishment of filling should be the same on the first pick of the shuttle as exists during subsequent weaving, and many attempts have been made to secure this result but with only partial success if at all. Should the tension on the thread during the first pick of the shuttle following replenishment differ from that during subsequent weaving, which is usually the case, the lack of uniform tension will be reflected in the finished cloth, especially when weaving with certain kinds of filling, such as silk, artificial silk, rayon and the like.

It has been proposed heretofore to provide a rigid tensioning member extending longitudinally of the shuttle and about which the thread is wrapped in one or more turns on the first pick of the shuttle following replenishment, but in such case reliance is placed entirely upon the frictional engagement of the thread with the rigid arm. During weaving, however, the thread will at times exert a pull from the shuttle and at other times become slack, so that the rigid arm heretofore employed will not function to take up the slack thread, with the result that frequently the tension will vary during the picking movements of the shuttle.

One of the objects of the present invention is to provide an automatically-threading loom shuttle with a plurality of tensioning members extending longitudinally of the shuttle and about which as a unit the thread is passed or wrapped on the first pick of the shuttle following replenishment, and to provide at least one of the plurality of tensioning members with resiliency or yielding movement under the pull of the thread towards or from the other tensioning member

or members, so that during the weaving operation the tensioning members may yield within the thread windings during the pull of the thread and then act to take up slack.

In carrying the invention into effect, the plurality of tensioning members have their ends which are remote from the bobbin chamber secured to the shuttle, from which point the tensioning members extend towards the bobbin chamber, where their ends are free, so that relative movement of the tensioning members towards and from each other will serve the desired purpose of maintaining uniform tension on the thread throughout the weaving operation.

As a further feature of the present invention, a thread director is provided at the free end portions of the tensioning members to direct the swirling thread about the tensioning members as a unit when the shuttle is first picked following replenishment, and the thread director is so constructed that when the thread has been wrapped about the plurality of tensioning members it will enter towards the central portion of the thread director and thereafter lead through the longitudinal passage in a serpentine or spiral course about the tensioning members.

The invention and novel features thereof will best be made clear from the following description and the accompanying drawings of one good, practical form thereof.

In the drawings:

Fig. 1 is a plan view of an automatically threading shuttle provided with the present invention, some of the parts being broken away;

Fig. 2 is a transverse section on the line 2—2 of Fig. 1;

Fig. 3 is a longitudinal section on the line 3—3 of Fig. 1, showing also the thread as wrapped about the tensioning members;

Fig. 4 is a view similar to that of Fig. 1, showing a modified form of the invention; and

Fig. 5 is a plan view of the modified form of the invention with parts broken away and showing the shuttle as completely threaded.

The shuttle 1 may be of the usual filling replenishing type provided with the bobbin chamber 2 in which the bobbin 3 is detachably supported in order to permit replenishment by the transfer of a fresh filling carrier or bobbin in the shuttle and the ejection of the spent one, but since such form of the replenishing shuttles is now well-known, further description and illustration of these features are unnecessary.

Forward of the bobbin chamber 2 is the longitudinal thread passage 4, and communicating with the thread passage is the side delivery eye 5, and these parts may be of usual character.

Filling replenishing shuttles which are automatically threaded during the loom operation are usually provided with a threading block, of which there are many types, so that on the first pick of the shuttle following replenishment the thread may enter the longitudinal thread passage and thus become partially threaded, and on the next pick of the shuttle the thread may be passed for delivery to the side delivery eye. The threading block 6 is shown as a top plate which is secured to the shuttle by a screw or bolt 7 passed through a side projecting flange of the top plate, and from said flange the top plate extends forwardly to form a thread deflector 8 between which and the shuttle body 9 is a passage 9 leading to the side delivery eye. The top plate, in the present instance of the invention, extends towards one side of the longitudinal thread passage where an opening 10 is formed to permit the thread to pass downwardly from the top plate into the longitudinal thread passage on replenishment of filling, as indicated in Fig. 1, where it will be noted that the thread *a* leading from the filling carrier or bobbin is passed downwardly from the top plate into the longitudinal passage, the shuttle being shown as having been supplied with a fresh filling carrier or bobbin having thread wound thereon. The construction thus far described may be of any usual character to effect preliminary threading of the shuttle on the first pick thereof following replenishment.

Mounted on the shuttle are the tensioning members, the ends of which remote from the bobbin chamber are secured to the shuttle, and the ends adjacent the bobbin chamber are free, and while two such tensioning members are shown in the present instance of the invention, there may be any convenient number. In any case, however, one at least, of the tensioning members shall be yielding or resiliently movable towards and from the companion tensioning member or members.

As shown in Figs. 1, 2 and 3, the tensioning members 11 and 12 extend longitudinally of

the thread passage and are preferably, though not necessarily, provided with bends, as shown, throughout the main portion of their length. The ends of the tensioning members remote from the bobbin chamber are mounted upon a screw or pin 13 which extends upwardly at the forward end of the thread passage, as shown, and is held in place by the nut 14. The ends of the tensioning members remote from the bobbin chamber are turned about the pin or bolt 13, as indicated at 15 and 16, and are clamped in place on the pin or bolt by means of an internally threaded sleeve 17 which serves to secure the ends of the tensioning members remote from the bobbin chamber in fixed position.

In the present illustration of the invention, the pin or bolt 13 and clamping sleeve 17 are disposed at one side of the longitudinal center of the thread passage, and in such case the end portions of the tensioning members extend from the bends 15 and 16, as shown by dotted lines, Fig. 1, at 18, and from the ends of the portions 18 the tensioning members 11 and 12 extend longitudinally of the thread passage towards the bobbin chamber where their ends are free or unconnected with the shuttle.

At the free end portions of the tensioning members there is a thread director, the function of which is to cause the swirling thread on the first pick of the shuttle following replenishment to be guided about the plurality of tensioning members as a unit, as indicated in Fig. 3. The thread director may be variously contrived but in the present instance of the invention it is formed of a generally circular or curved member 19 which is secured to one of the tensioning members, as, for instance, the tensioning member 11, as indicated in Fig. 1, and the other tensioning member 12 is unconnected with the thread director but extends therethrough, and may be provided with a knob or enlargement 20 to insure the continuous operative position of parts.

The thread director, as more clearly shown in Fig. 2, consists of a curved member carried by the tensioning member 11, and provided with an opening 21, whereby when the thread has been wrapped about the tensioning members as a unit on the first pick of the shuttle following replenishment, the thread will be directed through the opening 21 and thereafter lead through the thread director to the wrappings on the tensioning members.

Since one of the purposes of the present invention is to provide for yielding movement of the tensioning members relatively within the wrappings of the thread to respond to the pull of the thread during weaving and maintain tension thereon, and to take up slack when the thread is relieved of pull, the tensioning members, or at least one of them, are

made resilient. As shown in the present instance of the invention there are two tensioning members 11 and 12, and both of them are resilient, but this may not always be necessary since resiliency of one may be sufficient in some instances.

In the modification shown by Figs. 4 and 5, the tensioning members are, or may be, of substantially the same character as shown by Figs. 1, 2 and 3, but instead of mounting both of the tensioning members upon the pin or threaded bolt 13, one of them may be mounted upon such pin or bolt as indicated in Figs. 4 and 5, and held in fixed position to extend longitudinally of the thread passage. In these respects the tensioning member 11 in Figs. 4 and 5 is the same as the similar tensioning member 11 in Figs. 1, 2 and 3.

In the modified form of the invention, however, the companion tensioning member 12, which is generally similar to the corresponding tensioning member of Figs. 1, 2 and 3, has its end remote from the bobbin chamber turned outwardly at 22, and its end portion secured by a screw or bolt 23 in a recess 24 formed in the side wall of the shuttle. In this case the end 22 is pivotally supported by the screw or bolt 23 and its terminal portion is bent outwardly at 25 where it is secured to a spring member 26 which may be conveniently formed as a rubber strip the opposite end portion of which is connected to a bolt or screw 27, as indicated more clearly in Fig. 5, with the result that the tension exerted on the tensioning member 12 may be adjusted at times by turning the bolt or screw 27.

Where the tensioning member 12 is mounted as just described, it may be desirable in most instances to place a cap or covering 28 over the recess 24 in the side wall of the shuttle.

In the modified form of the invention, as in the preferred form, the thread director 19 is carried by the free end of the tensioning member 11 and the free end of the tensioning member 12 extends through the thread director 19, as indicated in Fig. 4, and beyond the thread director the tensioning member 12 is provided with an enlargement 20 as in the preferred form of the invention.

When filling replenishment is effected, the thread *a* from the filling carrier or bobbin will pass below the top plate of the threading block into the longitudinal thread passage, and when the shuttle is picked following replenishment the swirling thread will be guided by the director 19 about the plurality of tensioning members as a unit and the coils of the thread will take a spiral formation, as indicated in Figs. 3 and 5, about the two tensioning members and be held in their spiral relation by the bends 29. When a number of turns of thread have been wrapped about the tensioning members and the thread leads

from near the free ends of the tensioning members, it will then be directed by the thread director 19 through the opening 21 thereof, with the result that the thread will thereafter lead through the thread director, as indicated in Figs. 3 and 5.

During the weaving operation, the tensioning members 11 and 12 will exert a certain amount of frictional retardation to the withdrawal of the thread from the shuttle by reason of the thread wrappings about the plurality of tensioning members and by their relative yielding movement towards and from each other they, or one of them, will be deflected so as to exert a yielding action upon the thread, and the tensioning members will thereupon move to a more or less degree towards each other, thereby yielding to the thread pull, as indicated in Fig. 5. When the thread becomes slack, however, the tensioning members will separate relatively and thereby take up slack, so that during the entire weaving operation the relative resiliency of the tensioning members will maintain tension upon the thread and also act to take up slack.

It may be desirable to guide the thread from the longitudinal thread passage to the side delivery eye and this may be readily effected by a post, which is furnished in the present instance of the invention by the clamping sleeve 17 which is located near the side delivery eye and about which the thread may lead, as indicated in Figs. 3 and 5.

What is claimed is:

1. An automatically threading loom shuttle having a bobbin chamber, a longitudinal thread passage and a side delivery eye communicating therewith, a plurality of thread tensioning members constituted as arms extending longitudinally of the thread passage in spaced relation to each other and having their ends remote from the bobbin chamber secured to the shuttle and their ends adjacent the bobbin chamber free that the swirling thread may be wrapped about the plurality of spaced tensioning members as a unit by the swirling or revolving movement of the unwinding thread when the shuttle is picked and the tensioning members act within the thread wrappings under the pull of the thread and take up slack.

2. An automatically threading loom shuttle having a bobbin chamber, a longitudinal thread passage and a side delivery eye communicating therewith, a plurality of thread tensioning members constituted as arms extending longitudinally of the thread passage having their ends remote from the bobbin chamber secured to the shuttle and their ends adjacent the bobbin chamber free that the swirling thread may be wrapped about the plurality of tensioning members as a unit when the shuttle is picked and the tensioning members act within the thread wrappings under the pull of the thread and

take up slack, and means for directing the swirling thread about the tensioning members to cause it to be wound upon said members by the swirling or revolving movement imparted to the thread as it unwinds from the filling carrier.

3. An automatically threading loom shuttle having a bobbin chamber, a longitudinal thread passage and a side delivery eye communicating therewith, a plurality of thread tensioning members having their ends remote from the bobbin chamber secured to the shuttle and their ends adjacent the bobbin chamber free and diverging outwardly that the swirling thread may be wrapped about the plurality of tensioning members as a unit by the swirling or revolving movement of the unwinding thread on the first pick of the shuttle following replenishment and the tensioning members may act within the thread wrappings to tension the thread and take up slack.

4. An automatically threading loom shuttle having a bobbin chamber, a longitudinal thread passage and a side delivery eye communicating therewith, a plurality of thread tensioning members constituted as resilient arms extending longitudinally of the thread passage having their ends remote from the bobbin chamber secured to the shuttle and their ends adjacent the bobbin chamber free that the swirling thread may be wrapped about the plurality of tensioning members as a unit by the swirling or revolving movement of the unwinding thread when the shuttle is picked and the tensioning members act within the thread wrappings under the pull of the thread and take up slack.

5. An automatically threading loom shuttle having a bobbin chamber, a longitudinal thread passage, and a side delivery eye communicating therewith, two thread tensioning members, one of which is yieldable towards and from the other and both extending longitudinally of the thread passage with their ends remote from the bobbin chamber secured to the shuttle and having their ends adjacent the bobbin chamber free that the swirling thread may be wrapped about both tensioning members as a unit by the swirling or revolving movement of the unwinding thread when the shuttle is picked and be subjected to tension by the combined action of the tensioning members.

6. An automatically threading loom shuttle having a bobbin chamber, a longitudinal thread passage, and a side delivery eye communicating therewith, two thread tensioning members, one of which is yieldable towards and from the other and both extending longitudinally of the thread passage with their ends remote from the bobbin chamber secured to the shuttle and having their ends adjacent the bobbin chamber free that the swirling thread may be wrapped about both tensioning

members as a unit when the shuttle is picked and be subjected to tension by the combined action of the tensioning members, and a thread director at the free ends of the tensioning members for directing the thread about said members.

7. An automatically threading loom shuttle having a bobbin chamber and side delivery eye, a plurality of thread tensioning members between the bobbin chamber and side delivery eye extending longitudinally of the shuttle and having their ends remote from the bobbin chamber secured to the shuttle and their ends adjacent the bobbin chamber free, and a thread director at the free ends of the tensioning members for directing the thread about said tensioning members as a unit when the shuttle is picked following replenishment to cause the thread to be wound upon the tensioning members by the swirling or revolving movement imparted to the thread as it unwinds from the filling supply.

8. An automatically threading loom shuttle having a bobbin chamber, a longitudinal thread passage and a side delivery eye communicating therewith that the shuttle may be automatically threaded, a plurality of thread tensioning members constituted as relatively resilient arms extending longitudinally of the thread passage having their ends which are remote from the bobbin chamber secured to the shuttle and their opposite ends free, one of said arms having a curved thread director at its free end that the thread may be wrapped about the plurality of arms as a unit when the shuttle is picked following replenishment of filling, the arms thereupon acting within the thread wrappings to tension the thread and take up slack.

9. An automatically threading loom shuttle having a bobbin chamber, a longitudinal thread passage and a delivery eye communicating therewith, two thread tensioning members constituted as arms extending longitudinally of the thread passage, one of which at least is yieldable towards and from the other and both having their ends remote from the bobbin chamber secured to the shuttle and their opposite ends adjacent the bobbin chamber free and constructed so that the thread will be wrapped about said arms as a unit by the swirling or revolving movement imparted to the thread as it unwinds from the filling supply on the first pick of the shuttle following replenishment of filling that the arms may act yieldingly within the thread wrappings to tension the thread and take up slack.

10. An automatically threading loom shuttle having a bobbin chamber, a longitudinal thread passage and a delivery eye communicating therewith, two thread tensioning members constituted as arms extending longitudinally of the thread passage, one of which at least is yieldable towards and from the other

and both having their ends remote from the bobbin chamber secured to the shuttle and their ends adjacent the bobbin chamber free so that when the thread is wrapped about said arms as a unit on the first pick of the shuttle following replenishment of filling the arms may act yieldingly within the thread wrappings to tension the thread and take up slack, and a curved thread director having an opening through which the thread passes after it has been wrapped about the tensioning members.

In testimony whereof, I have signed my name to this specification.
